BUILDING CONSTRUCTION

Thomas Edward King, Hartsdale, N. Y., assignor
to Lord & Burnham Company, Irvington, N. Y.,
a corporation of New York

Application February 2, 1944, Serial No. 520,719

4 Claims. (Cl. 20—4)

This invention relates to building construction and more particularly to prefabricated buildings which are generally made to certain specifications and assembled on the location on which they are to be used.

In illustrating my invention I have shown it adapted to a simple construction in which the structure is made mostly of glass. However, this is purely for the purposes of illustration and it is applicable to structures where wall panels and other materials are used.

In this type of construction buildings are assembled in a plurality of sections. Each sash joins another to a flat surface. Bolts normally extend through and hold the sash side by side in a secure manner but the joint is normally one between two smooth edges. Wood is normally used as the structural material and due to its characteristics it will not always stay absolutely straight. It sometimes happens that two stiles of the sash do not touch even though they may be bolted securely together. This leaves an opening through which wind and rain may penetrate.

An object of this invention is to provide a simple construction which will more securely close the joints and which will provide means to carry off any water which works its way through the outside of the joint.

Other objects and advantages of my invention will appear as the description proceeds.

In the accompanying drawing—

Figure 1 is a perspective view of a greenhouse constructed in accordance with my invention;

Fig. 2 is a cross sectional view of a joint between two sash taken on the line 2—2 of Figure 1;

Fig. 3 is a detailed perspective view of a sash;

Fig. 4 is a detailed perspective view of a half spline.

Referring more particularly to the drawing a greenhouse 10 is constructed of a series of panels or sections 11, 12, 13 and 14 and may consist of as many sections as desired. These sections may be of sash construction and are provided with stiles 15 and 16 at their edges. The stiles are bolted to a connecting stile by means of the bolt 17 extending through the opening 18. Each of the stiles carry the panel 19 fitted in the groove 20. As shown in the drawing panel 19 is glass but may be of any other material suitable for building purposes. Each of the splines 15 and 16 are provided on their joining surface 25 with a concave drip groove 26 which forms with the corresponding drip groove on the adjoining stile a heart-shaped drip groove 27 adapted to carry

off any water which might leak or work its way through the joint at 28. The adhesion between the water and the walls of the heart-shaped drip groove 27 will cause the water to travel along the walls and down into the two concave drip grooves 26 which form the troughs of said heart-shaped drip groove 27.

In order to further secure the structures against leakage of water or air a half spline 30 is provided and the stiles 15 and 16 are rabbeted at 31 and 32 to receive the spline 30. While the rabbets are cut square the spline is slightly concave on its inner surface 32. It is provided with screw openings 33 on one side adapted to receive a screw 34 which extends into one of the stiles. Since the spline is slightly concave a screw on one side holds the spline tight on both sides and it is only necessary to place screws at intervals on one side. In addition to the foregoing the 20 concave shape of the spline causes it to act as a gutter to carry out any water which may be driven through the joint and not caught by the gutter 27 formed by the drip grooves 26.

It will be seen that my construction is simple 25 of manufacture and provides a water tight and generally wind-proof joint which may be readily prefabricated and assembled.

I claim:

1. In a building construction having a series 30 of sections joined together through their respective stiles of corresponding drip grooves in said stiles on the inner surface of said stiles, said drip grooves forming with each other a heart-shaped gutter spanning the joint, its apex pointing in the direction of the outside of the building, thereby providing non-communicating gutters on both sides of the joint into which any water seepage through the joint will pass in response to the force of adhesion exerted by the walls to said gutters.

2. In a building construction a joint comprising two members bolted together, the meeting edge of each of said members having a concave groove forming a heart-shaped drip gutter spanning the joint, its apex pointing in the direction of the outside of the building, thereby providing non-communicating gutters on both sides of the joint into which any water seepage through the joint will pass in response to the force of adhesion exerted by the walls to said gutters, the interior faces of each of said members being rabbeted and a spline member having a concave inner face fitted in said rabbeted portions forming an additional gutter.

3. In a building construction having members

bolted together to form a joint, a pair of non-communicating drip grooves on the meeting faces of said members into which groove any water seepage through the joint will pass in response to the force of adhesion exerted by the walls of said grooves, the interior edges of said members being rabbetted to define a rectangular opening, a spline in said opening, said spline being slightly concave, and screws holding said spline to one of said members.

4. In a building construction having members bolted together to form a joint, a pair of drip grooves on the meeting faces of said members

forming a drainage gutter spanning the joint and thereby providing non-communicating grooves on both sides of the joint into which any water seepage through the joint will pass in response to the force of adhesion exerted by the walls of said grooves, the interior edges of said members being rabbetted to define the rectangular opening, a spline in said opening having a concave inner face, said spline being fastened to one of said members and due to the concave face tightly contacting the other of said members.

T. EDWARD KING.
